(57) **CLAIM**

I claim the ornamental design for a carafe, as shown and described.

DESCRIPTION

FIG. 1 is a perspective view of the carafe embodying my new design;

FIG. 2 is a rear elevational view of FIG. 1;

FIG. 3 is a left side elevational view of FIG. 2;

FIG. 4 is a right side elevational view of FIG. 2;

FIG. 5 is a top plan view of FIG. 2; and,

FIG. 6 is a bottom plan view of FIG. 2.
